FIG. 1 is a perspective view of a bottle covering showing my new design;

FIG. 2 is a top plan view thereof; and
FIG. 3 is a bottom plan view thereof.

The portions shown in broken lines are for illustrative purposes only.

The dominant features of the design reside in the close basketweave lower peripheral portion, open net-like intermediate portion, and the thicker top strands which radiate from the intermediate portion upwardly and inwardly and which are adapted to overlie the shoulder of a bottle and extend to the neck.

I claim:

The design for a bottle covering, substantially as shown and described.
